[57] **CLAIM**

The ornamental design for a planter, as shown and described.

DESCRIPTION

FIG. 1 is a front perspective view of a planter showing our new design;

FIG. 2 is a front isometric view thereof;

FIG. 3 is a top plan view thereof;

FIG. 4 is a front elevational view thereof;

FIG. 5 is a rear elevational view thereof;

FIG. 6 is an end elevational view thereof;

FIG. 7 is an opposite end elevational view thereof; and,

FIG. 8 is a rear isometric view thereof.

With the exception of the raised sides, the undisclosed bottom plan view is identical to the top plan view.

FIG. 1**FIG. 2****FIG. 3****FIG. 4****FIG. 5****FIG. 6****FIG. 7**FIG. 8
